UNITED STATES PATENT OFFICE.

ALBERT L. ADAMS, OF CEDAR RAPIDS, IOWA.

COAL-CHUTE.

1,133,692.

Specification of Letters Patent. Patented Mar. 30, 1915.

Application filed March 26, 1914. Serial No. 827,451.

To all whom it may concern:

Be it known that I, ALBERT L. ADAMS, a citizen of the United States, residing at Cedar Rapids, in the county of Linn and 5 State of Iowa, have invented a new and useful Coal-Chute, of which the following is a specification.

The present invention relates to improvements in coal chutes, the primary object of 10 the invention, being the provision of a chute for attachment to or to be used in conjunction with a coal delivery wagon, the inlet end of the chute being provided with a removable reinforcing or auxiliary bottom to 15 thus receive the greatest impact and wear due to the initial impact of the coal entering the chute, the extreme edge of the reinforcing or auxiliary bottom being provided with two sets of spaced fingers which act as 20 guards to reduce the spilling of the coal due to an over-crowding at the mouth of the chute.

A further object of the present invention is the provision of a coal chute, in which an 25 auxiliary impact receiving bottom is insertible within the inlet end of the chute, and is provided with means to coact with the supporting lip of the chute at the end thereof to limit the distance of introduction of the 30 auxiliary bottom into the chute and also to prevent the same from sliding further relatively to and upon the bottom of the chute.

With the foregoing and other objects in view which will appear as the description 35 proceeds, the invention resides in the combination and arrangement of parts and in the details of construction hereinafter described and claimed, it being understood that changes in the precise embodiment of the invention herein disclosed can be made within 40 the scope of what is claimed without departing from the spirit of the invention.

In the drawings Figure 1 is a perspective view taken from the inlet end of a coal 45 chute, constructed according to and embodying the present invention. Fig. 2 is a longitudinal sectional view at the inlet end of the chute, clearly showing the manner of mounting the auxiliary bottom therein. 50 Fig. 3 is a section taken transversely of the chute upon the line 3—3 of Fig. 2.

Referring to the drawings, the numeral 1 designates the main body of the chute, which may be provided with parallel or tapering 55 guide walls 2, each of which is provided with the inturned guiding and strengthen-

ing flange 3. These flanges and the angle at their junction with the walls, are protected and further strengthened by the angle irons 3', which are preferably riveted in position. 60 The angle irons 3' adjacent the inlet end of the chute are each pierced by a rivet 4, as is also the wall 2 and the upper end of the band 5, which is secured to and embraces the outer end of the chute, and carries the lip or 65 flange 6, which provides a means to limit the outward movement of the chute relatively to the wagon.

In order to properly reinforce the bottom of the chute at its greatest wearing point, 70 which is at the portion beyond the lip 6, is the plate 7, which is substantially the width of the bottom of the chute, between the walls 2, said plate 7 being slidable and insertible from and in the inlet end of the chute to be 75 detachably held in place against upward displacement by the guiding cleats or fastenings 8, which are of such a size as not to interfere with the passage of the coal upon the plate 7 and between the walls 2. 80

To provide a means to prevent the coal from over-crowding and spilling from the inlet end of the chute and also to limit the introduction of the auxiliary bottom 7 within the chute and preventing it from sliding 85 farther therein, the flat fingers or prongs 9 and 10, are formed at one end of the plate 7, by producing parallel slits in the end thereof, and alternatingly bending the fingers 9 and 10 in opposite directions and at right 90 angles to the plane of the plate 7, the fingers when the plate 7 is in proper assembled position, being in a plane slightly beyond the outer face of the lip 6, as clearly shown in Figs. 1 and 2. 95

By this construction of coal chute, it is evident that the plate 7 will form a reinforcement for the bottom of the chute at the inlet end thereof, and that by reason of the fact that the same is removably secured in 100 place, the same may be removed by being slidably withdrawn through the inlet end of the chute and reversed when it itself is too greatly worn, the fingers 9 and 10, thus being properly positioned as they are so disposed as to project beyond either side of the plate 7. It will thus be seen that when the auxiliary bottom 7 is in position, the depending fingers 9 will abut the outer face of the lip 6 and thus limit the inward movement of the auxiliary bottom relatively to the inlet end of the chute, while the up- 110

wardly projecting fingers 10 will provide a barrier across the inlet end of the chute to prevent the back crowding of the coal which is delivered upon the auxiliary bottom 7.

5. What is claimed is:

1. A coal chute, a reversible slidably mounted auxiliary reinforcing bottom insertable through the inlet end of the chute for disposition above and in contact with 10 the main bottom of the chute to receive the initial impact of the coal dumped into the chute, and means attached to the side of the chute for engaging the upper surface at its edge of the auxiliary bottom for holding 15 the same relatively upon the main bottom of the chute.

2. A coal chute, a reversible and detachable auxiliary and reinforcing bottom mounted at the inlet end and oppositely extended and spaced fingers carried by the reinforcing bottom and for projection across the extreme inlet end of the chute to form a barrier to prevent the spilling of material due to the back crowding in the chute.

25. 3. A coal chute having a main bottom, a slidably mounted removable plate insertable at the inlet end of the chute to be placed co-extensive with the main bottom, said plate constituting an auxiliary covering bottom 30 for the main bottom of the chute, and guiding means attached to the sides of the chute and projecting in contact with the top surface of the edge of the removable plate for holding the plate upon the main bottom.

35. 4. A coal chute having the main bottom thereof at the inlet end reinforced by a slidably mounted reversible plate insertable at the inlet end of the chute to be placed co-extensive with the main bottom said plate 40 constituting an auxiliary covering bottom for the main bottom of the chute, guiding means for holding the plate upon the main bottom, and means for limiting the inward movement of the plate.

45. 5. A coal chute, a detachable plate constituting an auxiliary reinforcing bottom for the inlet end of the chute, said plate being provided with bent up spaced fingers to form a barrier across the extreme inlet 50 end of the chute.

55. 6. A coal chute, a detachable and reversible plate constituting an auxiliary reinforcing bottom for the inlet end of the chute, said plate being provided with two sets of spaced fingers formed at one end one set upon each side of the plate, said fingers forming barriers across and at the extreme inlet end of the chute.

7. A coal chute, having a bottom and up-

standing guiding walls, a retaining lip carried by the bottom and walls at the inlet end of the chute, a plate slidably mounted above and in contact with the bottom and insertable in the inlet end of the chute, said plate constituting an auxiliary bottom at 60 such point, and means carried by the plate and coöperating with the lip to limit the distance of insertion of the plate within the chute.

8. A coal chute, having a bottom and up-standing guiding walls, a retaining lip carried by the bottom and walls at the inlet end of the chute, a reversible plate slidable through the inlet end of the chute above and in contact with the bottom, said plate 70 constituting an auxiliary bottom for the chute, a barrier at the free end of the plate extending across the extreme inlet end of the chute, and guiding and fastening means to hold the plate upon the bottom of the 75 chute.

9. A coal chute, having a bottom and up-standing guiding walls, a plate slidable in the inlet end of the chute for disposition above and in contact with the bottom, said 85 plate constituting an auxiliary bottom for the chute at such point, and oppositely extending spaced fingers carried by one end of the plate for projection above and below the bottom of the chute, the fingers below 90 constituting a means for limiting the insertion of the plate within the inlet end of the chute while the fingers above constitute a barrier to prevent the back crowding 95 of material out of the chute.

10. A coal chute, having a bottom and upstanding guiding walls, a plate slidable in and from the inlet end of the chute and constituting an auxiliary bottom for the chute at such point, and oppositely extending spaced fingers carried by one end of the plate for projection above and below the bottom of the chute, the fingers below constituting a means for limiting the distance 100 of insertion of the plate within the inlet end of the chute while the fingers above constitute a barrier to prevent the back crowding of material out of the chute, and means carried by the chute for guiding the plate and for holding the same relatively to and 110 above the bottom of the chute.

In testimony that I claim the foregoing as my own, I have hereto affixed my signature in the presence of two witnesses.

ALBERT L. ADAMS.
